(57) **CLAIM**

The ornamental design for a USB flash disk as shown and described.

DESCRIPTION

FIG. 1 is a perspective view of a USB flash disk showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the USB flash disk of FIG. 1, shown in a first alternate configuration; and,

FIG. 10 is a perspective view of the USB flash disk of FIG. 1, shown in a second alternate configuration.

The broken lines in the drawings depict portions of the USB flash disk that form no part of the claimed design.
